CLAIM

The ornamental design for a table top golf ball novelty, as shown and described.

DESCRIPTION

FIG. 1 is a perspective view of a table top golf ball novelty showing my new design;

FIG. 2 is a side view thereof with the ball in a lower position, the other three sides being of identical appearance;

FIG. 3 is a top view thereof, the opposed bottom being of identical appearance; and,

FIG. 4 is a sectional view thereof taken upon the line 4—4 of FIG. 2.

FIG. 1

FIG. 2

FIG. 3

FIG. 4
